UNITED STATES PATENT OFFICE.

WILLIAM HINCKLEY MITCHELL, OF NUTLEY, NEW JERSEY, AND ALEXANDER BON-
NELL TAPPEN, OF BRIARCLIFF MANOR, NEW YORK.

GRATING SUPPORT.

Application filed August 30, 1924. Serial No. 735,102.

To all whom it may concern:

Be it known that we, WILLIAM HINCKLEY MITCHELL, a citizen of the United States, residing at Nutley, in the county of Essex and 5 State of New Jersey, and ALEXANDER BON-NELL TAPPEN, a citizen of the United States, residing at Briarcliff Manor, in the county of Westchester, State of New York, have invented certain new and useful Im- 10 provements in Grating Supports, of which the following is a specification.

Our invention relates to improvements in grating supports.

In practice it has been found that metal 15 gratings used as floors or coverings for vaults, sidewalk openings and the like suffer serious deterioration by reason of the fact that pockets or traps, collecting dust and refuse form on the shelf angles or frames by 20 which the grating is supported, and moisture collecting therein causes rapid deterioration with consequent damage or destruction when the grating is subjected to strain or load.

25 An object of our invention is to provide a support which will overcome these defects.

A further object of our invention is to provide a support which will permit of ready replacement of damaged or weakened 30 parts.

A further object of our invention is to provide a support which cannot accidentally work out of place.

A further object of our invention is to 35 provide a supporting device in which the surfaces in contact are of minimum area.

A further object of our invention is to provide a grating support which will permit the grating to be easily removed without 40 leaving any obstruction in the vault opening.

We accomplish these objects by the device illustrated in the accompanying drawings, in which,

45 Fig. 1 is an illustration of the preferred form of our device,

Fig. 2 is a cross section of the same on the line 2—2 in Fig. 1.

Fig. 3 is a view of the device with locking pin and spring.

50 Fig. 4 is a view of the supporting bar and sockets,

Fig. 5 is a view of the device with optional form of locking means and

Fig. 6 is a section of the same on the line 6—6 in Fig. 5.

Similar characters of reference refer to similar parts throughout the several views.

At the margin of the opening which it is desired to cover by a grating 1 we provide an angle 2 to protect the edge of the sidewalk or floor. Sockets 3, 3¹ are provided on opposite sides of the openings. These sockets may be attached in any desired manner but we prefer to hang them on to angle 2 either by means of bolts 4 or the like or by casting them integral with the angle 2. These sockets are preferably applied when the floor or sidewalk is being laid but may be easily applied to an old floor or sidewalk.

Supporting bars 5 extending across the 70 opening from side to side are seated in the sockets 3, 3¹ and upon these bars 5 the grating panel rests.

We prefer to construct the supporting bars 75 5 of such length that they may be seated in their sockets after the sockets are in position and may be removed therefrom as desired. For this purpose, the length of the bar 5 is preferably slightly less than the distance from the inner depth of one of the 80 sockets 3 to the mouth of the opposite socket 3¹.

The sockets are arranged in pairs. One 85 socket 3 of each pair is preferably provided with an underhung lip 3² extending out beyond the margin of the sidewalk opening to serve as a rest and underguard for the bar 5.

We provide sufficient space 3³ in the socket 3¹ to permit the bar 5 to be inserted when inclined from a horizontal position.

90 It will thus be apparent that the bars 5 upon which the grating panel rests may be inserted or removed at pleasure.

It is desirable that an open space be left 95 around the grating so that there will be no pockets where dirt, refuse, snow, ice or the like may collect. For this purpose we prefer to space the supporting bars 5 two or three inches from the parallel walls of the grating space or vault opening.

The sockets 3, 3¹ are provided in pairs as above explained, at opposite sides of the

grating space, and the bar 5 is inserted in one socket 3¹ and then drawn out into the opposite socket 3 so that the ends of the bar 5 will be seated in the two opposite sockets, 5 as shown in Figure 4.

The underhung lip 3² will serve to prevent the bar 5 from falling even through it should work out of the socket, but to prevent accidental displacement of the bar 5 we prefer to provide means for locking the bar in position. One form of our locking means is illustrated in Figure 3, in which is shown a compression spring 8 in the socket 9.

The tension of this spring 8 serves to hold 15 the bar 5 in the opposite socket 10.

We also prefer in some cases to provide a pin 7 which is inserted in the bar 5 to hold it in position. This pin 7 may be used either with the spring 8 or without the spring as 20 may be desired.

When the pin 7 is used the underhung lip may be omitted and a socket 10 provided which does not project into the vault space.

A further optional form of the device is 25 illustrated in Figures 5 and 6. In this form of the device we provide a socket 11 having a seat 12. The end of the bar 5 is inserted in the socket 11 and drawn out until the opposite end is seated in its socket when the 30 bar will rest in the seat 12 and will be held in position by means of the shoulder 13 against which it rests.

We prefer in this form of the device to provide a key 14 which may be driven into 35 the socket 11 over the bar 5 to hold it firmly in position.

We have shown a round bar 5 as the pre-

ferred form of support but we do not intend to limit ourselves to any particular form of bar, as it is obvious that any form 40 or shape of bar may be used as conditions may render desirable.

We preferably lay the grating on the supporting bar without tying it thereto as the weight of the grating is ordinarily sufficient 45 to hold it in position particularly where heavy panels are used but our improved support readily lends itself to the use of any desired tie between the grating and bar which may be desired. 50

Having thus described our invention, what we claim is:

1. In a grating support, the combination of a grating, a plurality of sockets in an adjacent wall below the surface of the grating, a bar below the grating detachably inserted in the sockets and means for locking the bar in the sockets. 55

2. In a grating support, the combination of a grating, sockets adjacent the grating, a supporting bar below the grating and inserted in the sockets and means for detachably engaging the bar in the sockets. 60

3. In a grating support, the combination of a grating, sockets adjacent the grating, a supporting bar under the grating and having its ends set in the sockets and means for locking the bar detachably in the sockets. 65

In testimony whereof, we have signed our names to this specification, this 25 day of 70 August 1924.

WILLIAM HINCKLEY MITCHELL.
ALEXANDER BONNELL TAPPEN.
